CIRCUIT BREAKER

Jerome Sandin, Forest Hills, and Robert H. Nau, Wilkinsburg, Pa., assignors to Westinghouse Electric & Manufacturing Company, East Pittsburgh, Pa., a corporation of Pennsylvania.

Application July 27, 1939, Serial No. 286,822

10 Claims. (Cl. 200—172)

The invention relates particularly to circuit breakers of the type used in controlling lighting and moderate power distribution systems.

Circuit breakers of the above-mentioned type usually embody relatively complicated operating mechanisms which should not be dismantled outside of the manufacturing or assembling plant. The operating mechanism is usually equipped with a pivoted metal operating member which has a handle of molded insulating material riveted or otherwise rigidly and non-removably secured thereto. This operating member forms a part of the operating mechanism and has the relatively powerful overcenter actuating springs, and in many cases other parts of the mechanism, connected thereto. It is apparent that if the molded handle is broken, the mechanism must be dismantled to replace it. This results in excessive servicing charges and also in undesirable service interruption.

An object of the invention is the provision of a circuit breaker of the class described with a molded insulating handle that is removably mounted on the metal operating member of the circuit breaker operating mechanism so that the handle may be removed or replaced without dismantling the mechanism.

Another object of the invention is the provision of a circuit breaker of the class described in which the molded insulating handle is rigidly secured to a metal mounting plate which reinforces and strengthens the handle without occupying more space, the handle and its rigid mounting plate being removably mounted on the metal operating member of the circuit breaker operating mechanism.

Another object of the invention is the provision of a circuit breaker with a removable handle of molded insulating material which is attached in a novel manner to a metal mounting plate by means of which it is removably mounted on the operating member of the circuit breaker.

The features of the invention which are believed to be novel are particularly pointed out in the appended claims. For a complete understanding and disclosure of the invention, reference may be had to the following detailed description of the invention to be read in conjunction with the accompanying drawings, in which:

Figure 1 is a fragmentary vertical sectional view of a three-pole circuit breaker embodying the features of the present invention, the section being taken substantially through the center pole of the breaker and certain parts being shown in elevation;

Fig. 2 is a fragmentary sectional view of the circuit breaker operating member and the re-

movable insulating handle taken substantially along the line II—II of Fig. 3;

Fig. 3 is a fragmentary sectional view of the operating member and handle taken at right angles to that of Fig. 2 substantially along the line III—III of Fig. 2;

Figs. 4, 5 and 6 are perspective views of the molded insulating handle, the metal mounting plate therefor, and the breaker operating member;

Fig. 7 is a fragmentary sectional view of a removable insulating handle showing a modified construction of attaching the molded handle to its metal mounting plate;

Fig. 8 is a fragmentary sectional view of a further modified handle construction and mounting on the metal operating member of a different circuit breaker construction;

Figs. 9 and 10 are perspective views of the operating member and handle shown in Fig. 8.

Referring to Figure 1 of the drawings, the circuit breaker shown is of the three-pole type. With the exception of the operating handle construction and its mounting, this circuit breaker is of the same general construction as the breaker fully described in Patent No. 2,083,304 of Ture Lindstrom, issued June 8, 1937, and assigned to the assignee of the present invention. Only a brief description of the main breaker construction will be given in this application. For details of the main breaker construction and its operation, reference may be had to the aforementioned patent.

The circuit breaker comprises, in general, a casing 9 of molded insulating material having a removable cover 11 secured thereon, stationary contact means 13, cooperating movable contact means 15, a circuit breaker operating mechanism 17, and a unitary trap device 21.

There are three sets of the stationary and movable contact means 13 and 15 forming the three poles of the breaker, only the contact means of the center pole being shown. The movable contact members 20 of the movable contact means 15 for the center pole are pivotally mounted at 22 on a movable switch member 23, and are biased toward the stationary contact means 13 relative to the switch member 23 by spring means 25 carried by the switch member, suitable stops 50 carried by the switch member being provided for limiting the counterclockwise movement of the contacts 20 relative to the switch member.

The switch member 23 is pivotally mounted by means of a pivot pin 26 on a U-shaped main frame 27 which also supports the circuit breaker operating mechanism 17. The movable contact means of the two outer poles (not shown) are also carried by switch members which are mechanically connected for simultaneous movement with the center pole switch member 23 by means

of a rigid tie bar 29 which extends transversely across the three poles of the circuit breaker. Each switch member is clamped to the tie bar 29 by a clamp 31, and the switch members are insulated from one another by means of an insulating sleeve 33 surrounding the tie bar 29.

The poles of the circuit breaker are insulated from one another by insulating barriers 31 molded in the casing 9, which align with similar barriers 39 molded in the cover 11. Each pole of the circuit breaker is provided with an arc-extinguishing structure 41 for extinguishing arcs drawn between the contacts during interruption of the circuit. The arc-extinguishing structures may be of any suitable type but are preferably of the type fully described in Patent No. 1,896,764, issued to M. W. Brainard, February 7, 1933, and assigned to the assignee of the present invention.

The electrical circuit for each of the poles of the breaker is substantially the same. The circuit for each pole extends from an upper terminal (not shown) through the arc-extinguishing structure 41 to the stationary contact means 13, and thence through the movable contacts 20, flexible shunt conductor 43, conducting bar 45, through the electro-responsive means of the trip device 21 to the lower terminal 47.

The operating mechanism 17 comprises the U-shaped frame 27, a pair of toggle links 49 and 51 having one end pivotally connected to the center pole switch member 23, a carrier lever 53 for releasably restraining the other end of the toggle links 49 and 51 in operative position, a channel-shaped operating member 55, an overcenter spring unit 57 for connecting the operating member to the knee of the toggle, and an operating handle 59.

The U-shaped frame 27 is positioned above the conductor bar 45 of the center pole and is rigidly secured to the base by means of screws 61 and 63. The screw 63 extends through the conductor bar 45 and hence the entire operating mechanism 17 and frame are at the same electrical potential as that of the center pole.

The toggle link 49 comprises a pair of parallel links which are joined by a bridge portion 65. One end of the toggle link 49 engages the center pole switch member 23 through the agency of a pivot pin 67. The other end of the toggle link 49 is pivotally connected to the upper end of the toggle link 51 by a knee pivot pin 69.

The toggle link 51 also comprises a pair of parallel link sections which are joined by a bridge portion 71 disposed at the upper end of the link beyond the knee pivot pin 69. The bridge portion 65 is adapted to engage the bridge portion 71 when the breaker is in the fully closed position, as shown, to provide a stop for defining the limit of upward motion of the knee of the toggle.

The overcenter spring unit 57 operatively connects the lower end of the operating member 55 with the knee pivot pin 69 of the toggle links and exerts a strong tension force therebetween. The lower end of the overcenter spring unit pivotally engages the lower end of the operating member 55 through the agency of a pivot pin 73 and a pair of supporting ears 75 carried by the operating member 55. The lower end of the toggle link 51 is pivotally connected to the carrier lever 53 by a pivot connection 77.

The channel-shaped operating member 55 has its sides pivotally connected to the frame 27 by means of a pivot pin 80. The carrier lever 53 comprises parallel bell crank levers which are

joined by a bridging section 79 which extends parallel to the base of the casing. The carrier 53 is pivoted to the frame at the apex of the bell crank levers by means of a pivot pin 81. The overcenter spring unit 57 at all times exerts a force on the carrier 53 transmitted through the toggle link 51, biasing the carrier lever in a clockwise direction, and a latching lever 83 is provided for restraining the carrier lever 53 in operative position. The latching lever 83 also comprises a pair of parallel sections which are joined by bridging portions 85 and 87. One end of the latching lever 83 is pivoted to the frame 27 by a pivot pin 89. The bridge portion 85 of the latching lever 83 normally overhangs and engages the bridge portion 79 of the carrier lever 53 and thus holds the carrier lever in an operative position by preventing it from moving in a clockwise direction under the bias of the operating spring 57 and the contact springs 25. The lower free end of the latching lever 83 is releasably restrained by pivoted latch-engaging mechanism 91 supported on the bridging portion 87, the latch mechanism 91 being normally restrained by a part of the trip device 21.

The trip device 21 is preferably of the type fully disclosed in Patent 2,043,306, issued to Jerome Sandin, June 9, 1936, and assigned to the assignee of the present invention. This trip device has a thermally responsive and a magnetically responsive element electrically connected in each pole of the breaker, and is operable upon the occurrence of predetermined overload conditions in any one of the poles of the breaker to effect release of the latching lever 83, and consequently, opening of all of the poles of the circuit breaker. Suitable means are provided for restoring the parts of the trip device to an operative condition following each tripping operation.

The operation of the circuit breaker as thus far described is briefly as follows. The operating handle 59 which is rigidly secured to the top of the operating member 55, is moved in a clockwise direction about the pivot pin 80 by its handle knob which projects through an elongated opening 82 in the top of the cover 11. When the operating handle has been moved a short distance, a projection (not shown) on the underside of the operating member engages the bridge portion 65 of the toggle link 49, and upon continued movement of the handle, positively sets the knee of the toggle in motion towards the base. At the same time, the operating spring unit 57 has been moved across the center line of the link 51, where it exerts a force tending to move the knee pivot pin 69 towards the base. The movement of the various parts of the operating mechanism is now automatic and all of the contacts are simultaneously opened with a snap action.

To close the circuit breaker, the operating handle 59 is moved in a counterclockwise direction about the pivot point 80, causing the line of action of the overcenter spring unit 57 to be moved over the center line of the toggle link 51. The operating spring unit then exerts a force biasing the knee pivot pin 69 outwardly from the base, causing extension of the toggle, and closing the contacts of the breaker also with a snap action.

When the breaker contacts are in the fully closed position and an overload or short circuit occurs in the circuit controlled by any one of the poles of the breaker, the latch-engaging mechanism 91 is released by the trip device 21 and the latching lever 83 then moves counterclockwise

about its pivot 89 under the biasing influence of the operating spring unit 57, transmitted thereto through the carrier 53. The counterclockwise movement of the latching lever 83 causes its bridge portion 85 to release the bridge portion 79 of the carrier lever 53. The carrier lever 53 is then moved clockwise about its pivot 81 under the biasing action of the overcenter spring unit 57 and the force of the contact springs 25, causing collapse of the toggle links and simultaneous opening of all of the contacts of the circuit breaker.

A pair of rollers 93 disposed on opposite sides of the channel-shaped operating member 55, are adapted to engage the edge of the parallel sections of the carrier lever 53 to limit motion of the operating member 23 in a clockwise direction, the rollers 93 also providing a means for resetting the carrier and latching levers following opening of the breaker by the trip device.

To reset the circuit breaker mechanism following an automatic tripping operation thereof, the operating handle 59 must be moved in a clockwise direction about the pivot axis 80 to its "off" position. This movement of the operating handle causes the rollers 93 to engage and reset the carrier lever 53 and the latching lever 83 to their latching positions. The breaker may then be reclosed by moving the operating handle in a counterclockwise direction to the "on" position.

Since the circuit breaker operating mechanism 17 is at the same electrical potential as the center pole of the circuit breaker, it is necessary that the operating handle 59 be of insulating material. Prior to the present invention, it has been the practice to provide an operating handle of molded insulating material, and to rigidly secure the molded handle to the metal operating member 55 by means of pin inserts molded into the handle, the ends of which pass through openings in the top of the operating member 55 and which were riveted over against the underside of the top of the operating member 55. The operating handle was thus rigidly but non-removably secured to the metal operating member. From the above description of the circuit breaker operating mechanism, it is apparent that the mechanism should not be dismantled outside of the manufacturing or assembly plant, due to the connection of the operating member 55 to the powerful tension spring 57 and other parts of the circuit breaker mechanism, and to the mounting arrangement of the various parts. Consequently, with the above-mentioned prior construction and non-removable mounting of the operating handle, excessive servicing charges and undesirable interruptions to service were incurred when the molded insulating handle was broken and had to be replaced.

According to the present invention, these difficulties are obviated by the provision of a molded insulating handle which is removably secured in a novel manner to the operating member 55. Referring to Figs. 1 through 6 of the drawings, the operating handle 59 comprises a handle 95 formed of molded insulating material and a metal mounting plate 97, which is rigidly secured to the underside of the molded handle 95. The molded handle 95 is provided with an elongated closure portion 99 which is adapted to close the opening 82 in the cover 11 in any position of the operating handle, and with a handle knob 101 which projects perpendicularly from the closure portion 99 intermediate the ends thereof and is adapted to extend through the opening 82 in the cover. The

metal mounting plate 97 is rigidly secured to the flat underside of the closure portion 99 of the molded handle 95 by means of a plurality of pin inserts 103, four in the embodiment shown, which are molded into the material of the closure portion 99. The pin inserts 103 have hollow end portions 105 (Fig. 4) projecting from the underside of the closure portion 99, which extend through openings 107 (Fig. 5) provided therefor in the metal mounting plate 97. The ends of the hollow projections 105 of the pin inserts 103 are swaged or riveted over against the underside of the mounting plate 97, thus rigidly securing the molded handle 95 to the mounting plate 97.

The handle mounting plate 97 is provided at one end with a pair of reversely bent flanges or hook portions 109, which are adapted to engage and hook over the upper edge of the top of the metal operating member 55 as shown in Fig. 2, 20 to mount the operating handle 59 on the operating member. The opposite end of the handle mounting plate 97 extends beyond the lower end of the closure portion 99 of the molded handle 95, and this end is provided with a plurality of openings 111 for receiving a plurality of mounting screws 113 which threadedly engage openings 115 (Fig. 6) provided therefor in the channel-shaped metal operating member 55. The operating handle 59 comprising the metal mounting plate 97 25 and the molded handle portion 95 is thus removably secured to the top of the metal operating member 55 by means of the reversed flanges or hooks 109 and the fastening screws 113. The side edges of the metal mounting plate 97 are 30 preferably bent inwardly to provide side flanges 117 which extend along the sides of the channel-shaped operating member 55, as shown in Fig. 3. The side flanges 117 serve to stiffen and strengthen 35 the handle mounting plate 97. The molded insulating handle 95 is also provided with side flanges 119 on opposite sides of the closure portion 99 thereof, which overlap the side flanges 117 of the metal mounting plate 97.

A slight modification of the invention is shown 45 in Fig. 7. In this modification, the molded handle 95' and the handle mounting plate 97' are of the same general construction as the embodiments shown in Figs. 2 through 5, with the exception of the manner in which the molded handle 95' is secured to the mounting plate. The molded handle 95' is secured to the metal mounting plate 97' in this modification, by a plurality of pins 120 which are rigidly secured to the mounting plate 97' and project upwardly 50 therefrom. The upper ends of the pin inserts 120 are provided with enlarged head portions 121, and the handle portion 95' is molded on the pins 120 directly against the mounting plate 97'.

If desired, the reverse flanges or hook portions 60 109 or 109' may be omitted, and this end of the metal mounting plate 97 extended beyond the upper end of the molded handle and provided with openings for receiving fastening screws which engage through this end of the mounting 65 plate and thread into openings provided in an extended portion of the top of the operating member 55 the same as for the lower end of the mounting plate. Also, as an alternative construction, the side flanges of the mounting plate may be made of greater width and the fastening screws passed through the side flanges into the sides of the operating member for removably securing the operating handle to the operating member.

A further modification of the invention is shown in Figs. 8, 9 and 10. In this modification the circuit breaker, only a portion of the operating mechanism of which is shown, is of the same construction as the circuit breaker disclosed in Patent No. 2,130,904, issued to Jerome Sandin, September 20, 1938, and assigned to the assignee of the present invention. For details of the complete construction and operation of the main circuit breaker structure, reference may be had to the above mentioned Sandin patent.

A yoke-shaped metal operating member 131 which forms part of the circuit breaker mechanism has legs 133 which are pivotally connected to the U-shaped frame 135 by a pivot pin 137. A pair of overcenter springs 139 (only one being shown) operatively connect the operating member 131 to the knee of the toggle links 141 and 143. The upper end of the toggle is restrained in operative position by a releasable carrier 145 which is normally held in operative position by a part of the trip device (not shown). The lower end of the toggle is pivotally connected to the center pole switch member (not shown).

The operating handle 147 is composed of molded insulating material and has an arcuate closure portion 149, downwardly projecting sides 151, and projecting handle knob 153. The underside of the closure portion has a recess 154 formed therein to closely fit the top of the metal operating member 131, and the sides 151 of the handle are provided with grooves 155 on their inner surface for closely fitting the legs 133 of the metal operating member when the handle is in mounted position on the operating member. A pin insert 157 is molded into the material of the handle in the center of the recess 154 and the projecting end of this pin fits closely but removably into an opening 159 provided there- 40 for in the top of the operating member 131.

The sides 151 of the operating handle are provided with screw receiving openings 161, and the handle is removably secured in mounted position by fastening screws 163 which pass into the openings 161 and thread into openings 164 in the legs 133 of metal operating member 131.

The load on the operating handle 147 during operation of the breaker is mainly transmitted to the yoke-shaped metal operating member 131 at the grooves 155 and at the pin insert 157. The load is also partially transmitted at edges of the recess 154, the ridges 156, and by the fastening screws 163. It is desirable to have a fairly close fit between the above-mentioned parts, otherwise the molded handle might be loose and certain portions are likely to be excessively stressed.

If the operating handle should break, it is only necessary to remove the screws 163 and slide the handle 147 off of the top of the operating member 131, and replace the handle by a new one.

In this modification as well as in all of the other embodiments, the screw fastenings which secure the handle to the operating member are inaccessible when the cover of the circuit breaker is on the casing, it being necessary to first remove the cover to obtain access to these screws. The molded handle in this last modification is also reenforced and strengthened by metal of the operating member.

The invention provides an insulating operating handle which in itself is reenforced and strengthened by a metal member on which it is mounted, and the handle is removably mounted on the metal operating member of the circuit

breaker mechanism. With this construction, the operating handle may be easily removed without dismantling the circuit breaker mechanism. Operating handles of this construction may be supplied to the customer so that in the event of handle breakage, a new operating handle may be substituted without undue interruption to the service.

10 The invention has been disclosed as applied to a specified type of circuit breaker. It is to be understood, however, that the invention is applicable to any type of circuit breaker having an operating mechanism of a construction which should not be dismantled.

15 While the invention has been disclosed in accordance with the provisions of the patent statutes, it is to be understood that various changes in the structural details thereof may be made without departing from the spirit of the invention. It is desired, therefore, that the language of the appended claims be given the broadest construction permissible in the light of the prior art.

20 We claim as our invention:

25 1. In a circuit breaker having relatively movable contacts, an operating mechanism for opening and closing said contacts, said operating mechanism having a metal operating member movably mounted on a fixed support for manually operating said mechanism, an operating handle having an enlarged base portion and an integral projecting handle portion both of molded insulating material, a metal mounting plate rigidly secured to the underside of the base portion of said operating handle by a plurality of short pin 30 inserts molded in the underside of the enlarged base of the operating handle, and means including said metal mounting plate for removably securing said operating handle to said metal operating member.

35 2. In a circuit breaker having relatively movable contacts, an operating mechanism for opening and closing said contacts, said operating mechanism having a metal operating member movably mounted on a fixed support for manually operating said mechanism, a movable operating handle having a handle portion of molded insulating material and a metal mounting plate rigidly secured to the underside of said molded handle portion, said metal plate having a reversely bent flange for engaging and hooking onto an edge of said metal operating member, and means including said flange for removably securing said operating handle to said metal operating member of the operating mechanism.

40 3. In a circuit breaker having relatively movable contacts, an operating mechanism for opening and closing said contacts, said operating mechanism having a metal operating member movably mounted on a fixed support for manually operating said mechanism, a removable operating handle having an enlarged base portion and an integral projecting handle portion both of molded insulating material, and a metal mounting plate rigidly secured to the underside of the base portion of said operating handle by a plurality of short pin inserts molded in the underside of the base portion of said operating handle, said plate having a portion extending beyond at 45 least one edge of said molded handle portion and provided with a plurality of openings for receiving mounting screws, said mounting plate being removably secured to said metal operating member by a plurality of mounting screws.

45 4. In a circuit breaker having relatively mov-

able contacts, an operating mechanism for opening and closing said contacts, said operating mechanism having a metal operating member movably mounted on a fixed support for manually operating said mechanism, a removable operating handle having a handle portion of molded insulating material and a metal mounting plate rigidly secured to the underside of said mounted handle portion, said mounting plate having a reversely bent flange at one end for engaging and hooking under an edge of said metal operating member, the other end of said mounting plate extending beyond the end of said mounted handle portion and having a plurality of openings for receiving mounting screws, said mounting plate and its rigid mounted handle portion being removably secured to said metal operating member by means of said flange and a plurality of mounting screws engaged in said openings and threaded into said metal operating member.

5. In a circuit breaker having relatively movable contacts, an operating mechanism for opening and closing said contacts, said mechanism having a yoke shaped metal operating member pivoted to a fixed support, and spring means connected to said operating member for actuating said contacts, an operating handle of molded insulating material having an enlarged integral base portion and an integral projecting handle portion both of the insulating material of the handle, said enlarged base portion and said operating member having closely interfitting portions which mainly transmit the force applied to said handle to said operating member during operation of the breaker and which permit removal of said operating handle from said operating member, fastening means for removably securing the base portion of said handle to said operating member, said fastening means being disposed to be secured and released from the outer side of said handle without disturbing any of the parts of said operating mechanism.

6. In a circuit breaker having relatively movable contacts, an operating mechanism for opening and closing said contacts, said mechanism having a yoke shaped metal operating member pivoted to a fixed support, and spring means connected to said operating member for actuating said contacts, an operating handle of molded insulating material having an enlarged base portion and an integral projecting handle portion, the inner side of the base portion of said handle having a recess therein to closely fit over the outer end of said yoke shaped operating member for mainly transmitting the operating force applied to said handle to said operating member, and means including a plurality of screws for removably securing said operating handle in mounted position on said operating member, said screws being disposed to be inserted and removed from the outside of said handle and operating member without disturbing any of the parts of said operating mechanism.

7. In a circuit breaker having relatively movable contacts, an operating mechanism for opening and closing said contacts, said mechanism having a yoke shaped metal operating member pivoted to a fixed support, and spring means connected to said operating member for actuating said contacts, an operating handle of molded insulating material having an enlarged base portion and an integral projecting handle portion, the base portion of said handle having sides pro-

vided with grooves which closely fit the legs of yoke shaped operating member, a projecting pin insert molded in the underside of the base section of the handle fitting closely in an opening provided therefor in the top of the operating member, and means for removably securing the handle in mounted position on said operating member.

8. In a circuit breaker, a casing of insulating material having a removable cover, circuit breaker operating mechanism in said casing having a metal operating member movably mounted on a fixed support in said casing, an operating handle of molded insulating material having a handle knob which projects through and is movable in an opening provided therefor in the cover and having an enlarged closure portion beneath said opening for closing said opening in any portion of said handle, means including one or more fastening screws for removably securing said handle on said operating member, said screws being disposed to be inserted or removed from the outside of said handle without disturbing any part of said mechanism, the major portion of the handle and all of the knob portion thereof which projects outside said casing being of solid insulating material.

9. In a circuit breaker, relatively movable contacts, operating mechanism for opening and closing said contacts including a metal operating member movably mounted on a fixed support for manually operating said mechanism, an operating handle having an enlarged base portion and an integral projecting handle portion both of molded insulating material, said operating handle having an inner surface conforming to the shape of the outer portion of the metal operating member to transmit the major portion of the operating force to the mechanism upon operation of the handle, one or more screws for removably securing said operating handle to said operating member, said screws being disposed to be inserted and removed from the outside of the handle without disturbing any of the parts of said mechanism, the major portion of said handle and all of the exposed portion of the handle projection thereof being of solid insulating material.

10. In a circuit breaker having relatively movable contacts, an operating mechanism for opening and closing said contacts including a yoke shaped metal operating lever pivoted on a fixed support for manually operating said mechanism, spring means connected in tension to said operating lever and movable thereby for actuating said contacts, an operating handle having an enlarged base portion and an integral projecting handle portion both of molded insulating material, said operating handle having an inner surface conforming to the shape of the outer portion of the metal operating lever to transmit the major portion of the operating force to said operating lever upon operation of the breaker by said operating handle, one or more fastening screws for removably securing said operating handle to said operating lever, said screw or screws being disposed to be inserted and removed from the outside of the operating handle without disturbing any of the parts of said mechanism, the major portion of said handle and all of the exposed portion of the handle projection thereof being of solid insulating material.

JEROME SANDIN.
ROBERT H. NAU.
